UNITED STATES PATENT OFFICE

2,446,831

THERMAL TIMING SWITCH APPARATUS

Frederick W. Hottenroth, Jr., Schenectady, N. Y.,
assignor to General Electric Company, a corporation of New York

Application February 12, 1944, Serial No. 522,117

10 Claims. (Cl. 200—122)

1

My invention relates to thermal timing apparatus, and particularly to ambient temperature compensated thermal timing devices which may be adjusted to operate either as impulse thermal timers or variable time recycling timers.

In thermally timing an operation, it has been common heretofore to energize a thermal responsive member to effect a desired control function after a timed interval and to maintain the thermal responsive member energized so long as the control function is exercised. Such an arrangement has the obvious disadvantage that, if it is desired to retime an interval immediately upon discontinuance of a control function, the thermal responsive member will not have sufficient time to return to its normal cooled position, and the desired timing operation will not be properly effected. To avoid such shortening or omission of a timing operation, it is desirable to use an impulse-type timer which, after timing an interval and initiating a desired controlled operation, automatically returns to its initial position without interrupting the continuation of the controlled operation. Such a timer positively ensures proper timing of the desired interval during each operation of the controlled apparatus.

Accordingly, it is a general object of my invention to provide a new and improved thermal timing apparatus which is inexpensive and easily assembled as well as efficient and reliable in operation.

It is a further object of my invention to provide a new and improved thermal timing apparatus which is compensated for changes in ambient temperature.

It is a still further object of my invention to provide a new and improved thermal timing apparatus of the impulse type which effects a locking-in operation of the controlled apparatus and automatically returns to its normal position.

It is still another object of my invention to provide a thermal impulse timer which requires resetting operation after each interval timing operation thereby to ensure proper interval timing.

It is still another object of my invention to provide thermal timing apparatus which may be adjusted to operate either as an impulse timer or as a recycling timer, there preferably being means provided for adjusting the periodicity of the cycling operation.

In accordance with the invention, the above and other objects are attained by providing, in a thermal timing device, a movable switch member connected for movement under the joint control of a pair of oppositely disposed thermal respon-

2

sive members, such as deformable bimetallic elements or the like. The movable switch member is arranged by its movement to control a snap-acting switch, the actuating member of which exhibits a definite differential between the positions at which it effects opening and reclosing of any pair of cooperating switch contacts. Suitable biasing means are provided for adjusting the normal position of the movable switch member. Thus, when the switch member is adjusted so that its normal position falls within the positional differential of the switch, the timer may be utilized as an impulse timer to effect a control function and return to its normal position without reversing the operation of the control switch. Resetting of the timing apparatus may then be effected by operating the switch member in the opposite direction to reset the switch and allowing it again to resume its normal position in preparation for the timing of another interval.

By so adjusting the normal position of the movable switch member that it is at or beyond one of the limits of positional differential of the switch, the timer may be used as a recycling timer in a manner to be more fully described hereinafter.

The nature of my invention will be more fully understood and its objects and advantages further appreciated by referring now to the following detailed specification taken in conjunction with the accompanying drawings in which Fig. 1 is a plan view of a thermal timing apparatus embodying my invention; Fig. 2 is a cross-sectional view taken along the line 2—2 of Fig. 1 looking in the direction of the arrows; Fig. 3 is a cross-sectional view taken along the line 3—3 of Fig. 1 looking in the direction of the arrows; Figs. 4, 5, 6 and 7 are schematic circuit diagrams illustrating various representative timing circuits including the timing apparatus shown at Figs. 1, 2 and 3; and Fig. 8 is a side elevation of a snap-acting switch of a type applicable in connection with my invention.

Referring now to the drawings, and particularly to Figs. 1, 2 and 3, the thermal timing apparatus therein illustrated to show one form which my invention may take comprises a casing 10, preferably formed of a suitable molded electric insulating material and provided with substantially perpendicular internal dividing walls 11, 12 and 13 separating the casing into a pair of adjacent upper compartments 14 and 15 and a lower compartment 16. The compartments 14, 15 and 16 are interconnected at the adjacent ends of the walls 11, 12 and 13, where the walls are spaced apart to provide space for a

movable switch member which is pivotally mounted upon a centrally located pivot pin 17. The pin 17 is supported in a U-shaped yoke 18 fixedly mounted upon the casing 10, as best shown at Fig. 3. The movable switch member comprises a U-shaped saddle 19 rotatably mounted upon the pivot pin 17 and having attached thereto an extending switch arm 20. The movable switch arm 20 extends from the saddle 19 into the compartment 16. The compartment 16 constitutes a switch compartment.

Also attached to the movable switch member at the bight of the U-shaped saddle 19 and extending in the opposite direction from the switch arm 20 and into the compartments 14 and 15 respectively, are a pair of flat thermal responsive bimetal elements 21 and 22. In the form of the invention shown in the drawing, the bimetal elements 21 and 22 are formed of a single strip of bimetallic material bent around a suitable seat formed by the base of the movable saddle 19 and riveted, or otherwise suitably attached, to the saddle. I wish to have it understood, however, that my invention is not limited to this particular manner of mounting the bimetallic elements, but that, if desired, the thermal responsive elements 21 and 22 may be formed of separate strips of bimetallic material and separately attached to the movable switch member.

The thermal responsive bimetal elements 21 and 22 extend from the saddle 19 through the compartments 14 and 15 and into engagement with a pair of abutments 24 and 25 formed upon the casing 10 adjacent the free ends of the elements 21 and 22. The bimetal elements 21 and 22 are initially slightly stressed against the abutments 24 and 25 and are arranged to be heated by electric heating elements 26 and 27, respectively, mounted within the compartments 14 and 15 in heat conductive relation to the elements 21 and 22. The compartments 14 and 15 serve thermally to isolate the heater 26 and bimetallic strip 21 from the heater 27 and bimetallic strip 22. The small passages connecting the compartments 14 and 15 with the compartment 16 are sufficiently large to accommodate the bimetallic strips 21 and 22, but are not sufficiently large to provide appreciable interchange of heat between the compartments.

Within the switch compartment 16 and in operative relation with respect to the movable switch member 21, is positioned a snap-acting overcenter electric switch 30 having an actuating member 35 and two pairs of electric switch contact terminals 36 and 37. For convenience, the switch contact terminals 36 may be wired to external binding posts 38. Preferably, the snap-acting switch 30 is of the type described and claimed in Patent 2,332,911 and shown at Fig. 8, issued to George M. Hausler on October 26, 1943. As described in that patent and shown at Fig. 8, this switch is an overcenter snap-acting switch having a bridging contact member arranged alternatively to bridge the stationary contacts connected to the pairs of terminals 36 or 37. The switch actuating member 35 is reciprocable to move the bridging contact member overcenter in both directions of movement, so that the dead center position of the actuating member will be slightly different in opposite directions. It will therefore be particularly noted that the switch 30 is of such a type that there is a small but definite movement differential between the positions of the actuating member 35 for opening and reclosing of any one pair of stationary contacts.

As described in the above-mentioned patent to Hausler, the switch actuating member 35 may be normally biased to one position. According to the present invention, the switch 30 is of such a type that the actuating member 35 is normally biased toward and into engagement with the movable switch arm 20, so that it tends to rotate the movable switch member in a counterclockwise direction, as viewed at Fig. 1. For the purpose of adjusting the normal position of the movable switch arm 20, a compression spring 40 is positioned between the switch arm and the side of the casing 10. Preferably, a nut 41 and an adjusting stud 42 are connected between one end of the spring 40 and the casing to provide an adjustable bias upon the movable switch member.

In order to adjust the thermal timing device described above for impulse timing operation, the biasing spring 40 is so adjusted that normally the switch arm 20 takes up a position intermediate its two spaced-apart switch actuating positions. That is, the normal position of the switch arm 20, when neither bimetallic element 21 or 22 is heated, is within and preferably midway within the positional differential of the snap-acting switch 30. Referring now to Fig. 4, where I have shown my timing apparatus connected as an impulse-type timer, this condition is indicated by the dotted lines 45 and 46 which indicate, respectively, the positions of the actuating member 35 for opening and reclosing the circuit through the switch terminals 37. The actuating member 35 is shown in a normal position C midway between the positions 45 and 46.

At Fig. 4 I have also shown the electric heating elements 26 and 27 connected to a suitable source of electric current supply through a pair of line conductors 47. The heater 26 is connected to the conductors 47 through the contact terminals 37 of the switch 30. The electric heating element 27 is connected to the line conductors 47 through a manually operable push button 48. I have also indicated at Fig. 4 that, when heated, the bimetallic elements 21 and 22 are so deformed that their free ends tend to move toward each other and away from their respective casing abutments 24 and 25.

In operation, the impulse timing apparatus illustrated at Fig. 4 functions in the following manner. Let it first be assumed that the apparatus is in the normal deenergized position, as shown, and that the circuit between the contact terminals 37 is closed. If now electric energy is supplied to the line conductors 47, only the electric heating element 26 will be energized and the free end of the bimetallic element 21 will tend to move away from the abutment 24 and toward the free end of the bimetallic element 22. However, because of the fact that the bimetallic elements 21 and 22 are initially stressed when in their unheated condition, heating of the bimetallic element 21 does not actually remove its free end from the abutment 24, but merely releases some of the stress in the element. This is equivalent to increasing the stress upon the bimetallic element 22 and results in rotating the movable switch member in a counterclockwise direction. As the movable switch arm 20 moves counterclockwise, as viewed at Fig. 4, the actuating member 35 of the snap-acting switch 30 follows under the influence of its own biasing spring until it reaches the position 45 where the circuit between the contact terminals 37 is broken. Thus, the electric heating element 26 is deenergized, so that the movable switch arm 20

ultimately returns to its normal center position C. In returning to this position, however, the switch 38 is not again actuated by reason of the fact that reclosing of the circuit between the contact terminals 37 does not take place until the actuating member 35 reaches the position 46. It will now be evident that the switch contacts connected to the pair of terminals 36 may be used to effect any desired control function, and that the timing device controls these contacts through a self-terminated impulse and effectually locks the contacts in position to maintain a controlled operation despite the fact that the movable switch member returns to its normal position.

If now it is desired to retime an interval by again closing the circuit between the contact terminals 36, it is first necessary to reset the timing apparatus by depressing the push button 48 to energize the electric heating element 27. When the electric heating element 27 is energized, the movable switch arm 20 is rotated in a clockwise direction, as viewed at Fig. 1, until the switch actuating member 35 reaches the position 46 to reset the switch with the contact terminals 37 bridged. The push button 48 may then be released to allow the movable switch arm 20 to return to its normal position. The cycle of operation may now be repeated to reclose the circuit between the contact terminals 36. It will of course be appreciated that preferably suitable interlocking means is provided to prevent reapplication of power to the controlled apparatus until the timing apparatus is reset with the circuit between the contact terminals 36 open.

By way of illustration of its many applications, the arrangement described above in connection with Fig. 4 has been found useful in timing the operation of a pump for maintaining circulation of the lubricating oil in an internal combustion engine for a predetermined period after the engine is stopped. For this purpose, the heater 26 is automatically energized upon cessation of engine operation and deenergized at its own interlock contacts in the manner described. The pump is deenergized when the switch 38 is actuated and, since the heater 26 is also deenergized at this time without reversing the switch operation, it is unnecessary to maintain the thermal element heated in order to prevent further pump operation. In order to reset the impulse timer, any desired suitable arrangement may be made automatically to energize the heater 27 for a short time in response to engine starting. If desired, of course, another interlock contact on the switch 38 may be used to deenergize the heater 27 as soon as the switch 38 is reset.

At Fig. 5, I have illustrated another embodiment of my invention in which the disposition of the bimetallic elements 21 and 22 is reversed, so that the free ends of these elements tend to move toward the abutments 24 and 25, respectively, and away from each other as heat is applied to the elements. In order to understand this embodiment of the invention, it may be noted that the bimetallic elements 21 and 22 may be positioned for deflection in either direction upon the application of heat thereto, it being only necessary that they be connected in opposition to each other. Thus, when heat is applied to the bimetal element 21 of Fig. 5 by the electric heating element 28, the stress in the bimetal element 21 is increased and the movable switch arm 20 rotated in a clockwise direction, as viewed at Fig. 5. This operation will be understood from the fact that an increase in stress of the bimetal element 21 is

equivalent to applying to the free end of the element 21 a force tending to move the free end toward the right, as viewed at Fig. 5. It will be noted from Fig. 5 that the electric heating element 28 is connected for control to the contact terminals 36 of the switch 38 rather than to the contact terminals 37. Since the circuit between the terminals 36 is open when that between the terminals 37 is closed, it will be understood that the open and closed positions 45 and 46, respectively, of the switch actuating member 35 are reversed with respect to those shown at Fig. 4, while the positional differential therebetween is the same. As at Fig. 4, the movable switch arm 20 is normally positioned at C midway between its opening and closing positions for the pair of contacts connected to the terminals 36.

The operation of the arrangement shown in Fig. 5 will be understood from the previous description of the operation of the arrangement of Fig. 4. Briefly, it may be noted that, if it is assumed that initially the contact terminals 36 are connected by the bridging contact of the switch 38 and heat is supplied to the bimetallic element 21 through the electric heating element 28, the movable switch arm 20 will be rotated in a clockwise direction, as viewed at Fig. 5, until the actuating member 35 reaches the position 45 to open the circuit between the contact terminals 36.

When the circuit between the terminals 36 is opened, the electric heating resistor 26 is deenergized and the movable switch arm 20 automatically returns to its normal central position without further affecting the switch contacts. In order to reset the switch, the electric heating element 27 is briefly energized to rotate the movable switch arm 20 in a counterclockwise direction to the position 46 whereupon the element 27 may be deenergized and the movable switch member 40 allowed to return to its normal central position.

Referring now to Fig. 6, I have illustrated schematically therein a circuit arrangement for utilizing my new and improved thermal timing apparatus as an automatic recycling timer with an adjustable periodicity. This form of the invention is characterized principally by the fact that the spring 40 of the timing device is so adjusted that the movable switch arm 20 is normally in the contact closing position for the interlock contact terminals 37 connected in series circuit relation with the electric heating element 26. That is, with respect to the heater control contact of the switch 38 the normal position of the switch arm 20 is adjusted to the closing limit of the positional differential of the switch. At Fig. 6, I have also shown a variable resistor 50 connected in series circuit relation with the electric heating element 27 to render the heating element 27 of less heating capacity than the element 26 and also to vary the degree of inequality between the heating elements 26 and 27 while maintaining the element 27 always of the smaller capacity. Attention is also directed to the fact that at Fig. 6 it has been assumed that the bimetallic elements 21 and 22 are so disposed that when heated their free ends tend to move toward each other and away from the casing abutments 24 and 25, respectively.

In operation, when energy is supplied to the line conductors 47 of Fig. 6, both heating elements 21 and 22 are simultaneously energized. The heating element 28, however, being of greater capacity than the element 27, heats the bimetallic element 21 to a greater extent than the bimetallic element 22 is heated, so that the net effect of heating both elements is to rotate the movable switch

arm 20 in a counterclockwise direction, as viewed at Fig. 6, thereby to move the switch actuating member 35 from the closed position 45 to the open position 46. At the position 45, the interlock contacts connected to the switch terminals 37 are open-circuited and the heating element 26 is deenergized. Energization of the heating element 27, however, is not interrupted, so that the bimetallic element 22 continues to receive heat as the element 21 cools. Under these conditions, the movable switch arm 20 is rotated in a clockwise direction, as viewed at Fig. 6, from the position 45 back to the position 46, thereby to reclose the interlock contacts 37 and to reenergize the heating element 26. It will now be evident that the foregoing cycle of operation will be repeated indefinitely and with a periodicity depending upon the difference in the heating capacities of the elements 26 and 27. Since the heating capacity of the element 27 is controlled by the variable resistor 50, it will be evident that the resistor 50 provides a means for adjusting the periodicity of recycling operation.

It will be understood from the foregoing explanation of Figs. 4 and 5 that if the bimetallic elements 21 and 22 of Fig. 6 are reversed so that their free ends tend to move apart and toward the casing abutments 24 and 25 when heat is applied thereto, the directions of rotation of the movable switch arm 20 will be reversed. In this event, recycling operation may be effected in the same manner as described in connection with Fig. 6 if the electric heating element 26 is connected for control to the switch terminals 36 and the initial position of the switch arm 20 is adjusted to the closing limit of positional differential for the contact terminals 36. Operation of this arrangement will be understood from the foregoing explanation of the operation of Fig. 6.

Referring now to Fig. 7, I have illustrated another recycling timer apparatus similar to that of Fig. 6, but in which the heater controlling contacts of the switch 39 are maintained normally open with the bimetallic elements 21 and 22 disposed in the same manner as in Fig. 6. The embodiment of Fig. 7 may be attained by adjusting the switch actuating member 35 to the opposite limit of the switch positional differential and leaving the heater 26 connected for control to the contact terminals 37. With such an arrangement, illustrated at Fig. 7, it will be observed that when electric energy is supplied to the conductors 47 only the heating element 27 is initially energized. Energization of only the element 27 effects the clockwise rotation of the switch arm 20, as viewed at Fig. 7, from the position 45 to the position 46, thereby to close the circuit of the electric heating element 26. When the heating element 26 of greater capacity than the element 27 is energized, the net effect of the heat applied to the bimetallic elements 21 and 22 will rotate the movable switch arm 20 in a counterclockwise direction, as viewed at Fig. 7, thereby to move the switch actuating member 35 from the position 46 to the position 45 and to reopen the circuit of the heating element 26. This recycling operation will continue indefinitely at a periodicity determined by the adjustment of the resistor 50.

It will be understood that, in the event that the bimetallic elements 21 and 22 of Fig. 7 are reversed so that, upon heating, their free ends tend to move apart and against the casing abutments 24 and 25, respectively, recycling operation may be effected by connecting the heating

element for control to the contact terminals 36 and resetting the normal position of the switch arm 20 to the opening limit of differential for the switch contacts connected to the terminals 36.

In view of the foregoing, it will now be evident that my invention provides a new and novel thermal timing apparatus which is simple in construction, reliable and rugged in operation, and extremely versatile in application.

10 While I have illustrated only certain preferred embodiments of my invention by way of illustration, many modifications will occur to those skilled in the art and I therefore wish to have it understood that I intend in the appended claims to cover all such modifications as fall within the true spirit and scope of my invention.

What I claim as new and desire to secure by Letters Patent of the United States is:

1. An ambient temperature compensated thermal timing apparatus comprising a movable switch member, a pair of thermal responsive members connected together in opposing relation and to said switch member jointly to control said switch member, separate electric heating means of unequal capacity disposed in heat conductive relation with said thermal responsive members, and a snap acting switch by said switch member and arranged to control only one of said electric heating means, said switch having a predetermined positional differential between circuit opening and circuit closing positions and being so positioned that said switch member normally lies at one limit of said differential.

2. An ambient temperature compensated thermal timing apparatus comprising a base, a pivotally mounted movable switch member, a pair of thermally deformable arms mounted upon said switch member and extending in substantially parallel spaced relation into abutting engagement with said base, said arms being disposed for deformation in opposite directions upon like changes in temperature, separate electric heating means for supplying heat to said arms, and a snap acting switch actuated by said switch member and arranged to control one only of said electric heating means, said switch having a predetermined positional differential between circuit opening and circuit closing positions and being so positioned that said switch member operates within said differential.

3. An ambient temperature compensated thermal timing apparatus comprising a base having a plurality of substantially thermally isolated compartments, a movable switch member pivotally mounted upon said base, a pair of thermally deformable arms carried by said switch member and extending in substantially parallel spaced relation into separate compartments of said base and into abutting engagement with said base, said arms being disposed for deformation in opposite directions upon like changes in temperature, separate electric heating means disposed in said compartments to supply heat to said arms, and a pair of cooperating switch contacts actuated by said switch member to control one of said electric heating means.

4. An ambient temperature compensated thermal timing apparatus comprising a base having a plurality of substantially thermally isolated compartments therein, a movable switch member pivotally mounted upon said base, a pair of thermally deformable arms carried by said switch member and extending through separate compartments into abutting engagement with said base, said arms being disposed

for deformation in opposite directions upon like changes in temperature, separate electric heating means in said compartments in heat conductive relation with said arms, an electric switch contact member actuated by said movable switch member and having a predetermined positional differential between contact opening and contact closing positions, said switch contact member being connected to control the energization of one of said electric heating means, and means for adjusting the normal position of said switch member throughout the limits of said positional differential.

5. A thermal impulse timer comprising a pair of thermal responsive members connected together in opposing relation, separate electric heating means disposed in heat conductive relation with said thermal responsive members, a switch member movable under the joint control of said thermal responsive members, a pair of cooperating switch contacts relatively movable by said switch member and connected to control the energization of only one of said electric heating means, said switch member having a predetermined positional differential between contact opening and contact closing positions and being normally positioned intermediate said opening and closing positions, and means for energizing said one electric heating means to time an interval, said other electric heating means when energized resetting said switch contacts.

6. A thermal impulse timer comprising a movable switch member, a pair of thermal responsive members connected in opposing relation jointly to control said movable switch member, separate heating means disposed in heat conductive relation with said thermal responsive members, a pair of snap-acting switch contacts actuated by said switch member and providing a predetermined positional differential between contact opening and contact closing positions of said switch member, said contacts being connected to deenergize one of said electric heating means when said switch member is moved a predetermined amount by the associated thermal responsive member, means for normally maintaining said switch member in a position intermediate said opening and closing positions, and manually operable means for energizing the other of said electric heating means to reset said switch contacts.

7. A thermal impulse timer comprising a base having a plurality of substantially thermally isolated compartments therein, a movable switch member pivotally mounted upon said base, a pair of thermally deformable bimetallic members mounted upon said switch member in cantilever fashion and extending through separate compartments into abutting engagement with said base, said bimetallic members being disposed for deformation in opposite directions upon like changes in temperature, separate electric heating means disposed in heat conductive relation with said bimetallic members, an overcenter snap-acting electric switch contact actuated by said switch member and providing a predetermined positional differential between contact opening and contact closing positions of said switch member, said switch contact being connected to deenergize one of said electric heating means when said switch member is moved a predetermined amount by the associated bimetallic member, and means for normally maintaining said switch

member in a position intermediate said opening and closing positions.

8. A recycling thermal timing apparatus comprising a pair of thermal responsive members connected together in opposing relation, separate electric heating means of unequal capacity disposed in heat conductive relation with said thermal responsive members, a switch member movable under the joint control of said thermal responsive members, a snap acting switch actuated by said switch member and arranged to control the energization of only said electric heating means of greater capacity, said snap acting switch having a predetermined positional differential between circuit opening and circuit closing positions and being so positioned that said switch member is normally positioned at one limit of said differential.

9. A recycling thermal timing apparatus comprising a movable switch member, a pair of thermal responsive members connected to said switch member in opposing relation, separate electric heating means of unequal capacity disposed in heat conductive relation with said thermal responsive members, a pair of cooperating switch contacts movable in opposite direction with a snap-action at spaced-apart switch actuating positions of said switch member and connected to control the energization of said electric heating means of greater capacity, and means for maintaining said switch member normally in one of said switch actuating positions.

10. A recycling thermal timing apparatus comprising a base having a plurality of substantially thermally isolated compartments therein, a movable switch member pivotally mounted upon said base, a pair of thermally deformable bimetallic members mounted upon said switch member and extending through separate compartments of said base into abutting engagement with said base, said bimetallic members being disposed for deformation in opposite directions upon like changes in temperature, separate electric heating means of unequal capacity disposed in said compartment in heat conductive relation with said bimetallic members, an electric switch contact member actuated by said movable switch member and having a predetermined positional differential between contact opening and contact closing positions, said switch contact member being connected to deenergize said electric heating means of greater capacity when said switch member is moved a predetermined amount under the predominant influence of the associated bimetallic member, and means for maintaining said switch member in a normal position at one limit of said positional differential.
